UNITED STATES PATENT OFFICE.

WILLIAM A. LORENZ, OF HARTFORD, CONNECTICUT.

DESIGN FOR A CAN OR JAR.

SPECIFICATION forming part of Design No. 35,414, dated December 10, 1901.

Application filed November 18, 1901. Serial No. 82,781. Term of patent 14 years.

To all whom it may concern:

Be it known that I, WILLIAM A. LORENZ, a citizen of the United States, residing in Hartford, in the county of Hartford and State of Connecticut, have invented and produced a new and original Design for Cans or Jars, of which the following is a specification.

My design relates to the external contour of cans, jars, and similar receptacles.

10 In the drawings, Figure 1 is a top view, and Fig. 2 is a side view, of a can or jar embodying my design.

The lower part 3 of the body of the jar is approximately cylindrical in contour, merging into the tapering upper part 4, which is approximately the length of the cylindrical body part 3. At the top of the tapering portion the jar is enlarged, forming a relatively narrow annular projecting band 5. This band 20 is surmounted by a top which is smaller in

diameter than the band 5 and comprises the comparatively narrow or annular bands 6 and 7, the latter of which is smaller in diameter than the former. These bands are separated by an intervening peripheral groove 8, which is substantially semicircular in cross-sectional outline.

Having described my invention, what I claim as new, and desire to secure by Letters Patent, is—

30 The design for a can or jar, substantially as shown and described.

In testimony whereof I have signed my name to this specification in the presence of two subscribing witnesses.

WILLIAM A. LORENZ.
